[57] **CLAIM**

The ornamental design for a retractable extension cord holder, as shown and described.

DESCRIPTION

FIG. 1 is a front elevational view of the retractable extension cord holder of the present invention;

FIG. 2 is a rear elevational view of the retractable extension cord holder of FIG. 1;

FIG. 3 is a left side elevational view of the retractable extension cord holder of FIG. 1;

FIG. 4 is a right side elevational view of the retractable extension cord holder of FIG. 1;

FIG. 5 is a top plan view of the retractable extension cord holder of FIG. 1; and,

FIG. 6 is a bottom plan view of the retractable extension cord holder of FIG. 1.

The claimed design is shown broken away to indicate indefinite length.
